GALLEY PUMP

Linus E. Russell, Springfield, Ohio, assignor to Peters and Russell, Inc., Springfield, Ohio, a corporation of Ohio

Filed Dec. 2, 1964, Ser. No. 82,872

Term of patent 14 years

(Cl. D65—1)

FIG. 1 is a side view of a galley pump embodying my design;

FIG. 2 is a top view thereof;

FIG. 3 is a front view thereof;

The dominant features of my design reside in the portions shown in full lines.

I claim:

The ornamental design for galley pump, substantially as shown and described.
